Inventor:

Lorenzo Dill

UNITED STATES PATENT OFFICE.

LORENZO DILL, OF UNION CITY, INDIANA.

LOOKING-GLASS FRAME.

SPECIFICATION forming part of Letters Patent No. 355,597, dated January 4, 1887.

Application filed October 1, 1885. Serial No. 178,781. (No model.)

To all whom it may concern:

Be it known that I, LORENZO DILL, a citizen of the United States, residing at Union City, county of Randolph, and State of Indiana, have invented a new and useful Article of Manufacture, of which the following is a specification.

My invention relates to improvements in a looking-glass frame in the form of a horseshoe, 10 with a bracket of the same form, and shelf attached, and has for its object to provide a simple and convenient device whereby the combination may be hung on the wall by means of a screw-ring attached to the toe of the bracket- 15 shoe, as is hereinafter fully described and claimed.

Reference is to be had to the accompanying drawings, forming part of this specification, in which similar letters of reference indicate 20 corresponding parts in both figures.

Figure 1 is a front view of my device. Fig. 2 is an edge view of the same.

The bracket is in the form of a horseshoe, and the shelf N provides the support for the 25 frame H, that encircles the glass. The shelf, when secured to the heel of the bracket-shoe S, extends back so that the bracket is at an

angle with the wall when hung up by the screw-ring L. The frame H swings on wires B B, secured to the back of the bracket S and frame 30 H by means of half-boxes R R and screws m m, so that the frame H may be turned in an angle to an upright position.

Having thus described my invention, what I claim as new, and desire to secure by Letters Patent, is—

As an improved article of manufacture, the herein-described looking-glass frame H and bracket S, provided with a ring, L, in the toe of the bracket for the purpose of suspension, 40 in combination with the shelf N, secured to the heel of the bracket S and extending backward from the same, the frame H being provided with wires B B and half-boxes R R, secured on the back of the frame H and the 45 bracket S by means of the screws m m, so that the glass may be turned at an angle, or placed in an upright position, substantially as set forth.

LORENZO DILL.
